UNITED STATES PATENT OFFICE.

GIOVANNI EMANUELE ELIA, OF WESTMINSTER, LONDON, ENGLAND, ASSIGNOR TO VICKERS LIMITED, OF WESTMINSTER, LONDON, ENGLAND, A BRITISH COMPANY.

SUBMARINE MINE.

Application filed February 2, 1924. Serial No. 890,218.

To all whom it may concern:

Be it known that I, GIOVANNI EMANUELE ELIA, a subject of the King of Italy, residing at Vickers House, Broadway, Westminster, 5 in the county of London, England, have invented certain new and useful Improvements in or Relating to Submarine Mines, of which the following is a specification.

This invention relates to submarine mines 10 of the kind provided with means for automatically causing the flotation chamber or mine proper to be anchored at a predetermined depth below the surface. The chief objects of the present invention are to provide 15 a form of anchoring mechanism which will be suitable for all types of submarine mines whether intended for use against surface craft or against submarine boats; to provide a construction of submarine mine in 20 which the flotation chamber is prevented from descending to such depths below the surface as would cause the same to be crushed or damaged by the hydrostatic pressure, and to provide a mine which is capable of being 25 anchored in any depth of water.

According to the present invention the flotation chamber, or the mooring cable at a point adjacent to the flotation chamber, is provided with a hydrostatically operated device 30 which controls the paying out gear for the mooring cable in such a manner that, when the said device is actuated, the mooring cable is allowed to pay out and the anchor to sink toward the sea bed, but the flotation chamber itself is prevented from descending below the depth for which the hydrostat has been set and at which it is intended that the flotation chamber should be anchored. To this end, the flotation 35 chamber may carry, or be provided with, hydrostatically operated mechanism for effecting the release of means, such as an electrically controlled brake, a solenoid or any other suitable locking or releasing device, positioned in the anchor and controlling the paying out gear for the mooring cable, the hydrostatically operated mechanism being initially set so as to come into operation at, or below, the depth at which the flotation 40 chamber is to be finally anchored and to release at such times the controlling means in the anchor so as to allow the mooring cable to pay out and the anchor to sink towards the sea bed, but serving to throw out 45 of operation the said controlling means in

the anchor and to stop the paying out of the mooring cable should the flotation chamber rise above the depth for which the hydrostat has been set.

In order that the said invention may be 60 clearly understood and readily carried into effect the same will now be described more fully with reference to the accompanying drawing which shows by way of example one constructional form of the said invention 65 and in which:—

Figure 1 is a diagrammatical view showing the sequence of operations of the mine during the laying operation.

Figure 2 is a sectional elevation of the 70 sinker also showing the lower part of the flotation chamber.

Figure 3 is a sectional plan view of an oil pump brake for controlling the paying out of the mooring cable the section being taken 75 in the line X, Y of Figure 2.

A is the flotation chamber. B is the anchor or sinker which contains the mooring cable drum C and which is provided with a seating b for the flotation chamber A, 80 the seating being connected to the sinker by a number of columns b¹. The mooring cable drum C is adapted to rotate in bearings b², b² in upper and lower plates b³, b³ forming part of the sinker B. The drum C has a 85 central chamber b⁴ which contains a battery D, a solenoid E and co-operating mechanism associated therewith for controlling the paying out of the mooring cable F as hereinafter explained. The mooring cable 90 F is constituted by a cable containing a pair of electric leads or conductors f, f which are in circuit with the battery D and with the coils of the solenoid E. The conductors f, f are connected at their upper ends 95 to spring controlled plungers f¹, f¹ which act as terminals. Attached to the flotation chamber is a hydrostatic switch G, the switch in the example shown comprising a diaphragm g which is acted upon by the hydrostatic pressure of the surrounding water and to which is attached a spindle g¹ the latter carrying a plate g² which, when the diaphragm g of the hydrostat is acted on by the predetermined hydrostatic pressure, overcomes the resistance of the spring g³ and bridges the terminals f¹, f¹ thus completing the circuit through the battery D and solenoid E. The hydrostat may also, as shown, be fitted with a non-return valve H, so that, in cases 100 105 110

where the mine is intended to be allowed to separate from the sinker at considerable depths, say from 30 to 200 feet, the chamber behind the diaphragm g may be filled with air through the valve F at the pressure corresponding to the hydrostatic pressure prevailing at the required depth, the operation of filling the hydrostat with compressed air being preferably performed by connecting to an air pump a pressure gauge specially calibrated to show the depths corresponding to different pressures. The mooring cable winch drum C is provided with a toothed wheel C^1 which engages with a pinion k forming part of an oil pump brake K , the pinion k being adapted to drive the gears k^1, k^2 of the said pump, so as to deliver the oil through the pipe or passage k^2 from the suction to the delivery side of the pump. In order that the pump may act as a brake, means, hereinafter described, are provided for choking to the required extent the said return passage k^2 . To this end the tube k^2 is formed in two parts whose ends communicate with an opening l formed within a casing L attached to the cover plate of the anchor. Adapted to move within the said opening so as partially or wholly to obturate the same is a piston valve m having a reduced portion m^1 , the piston being connected to a light tubular spindle n located within the solenoid E . At its lower end the spindle n is slidably mounted upon a tube n^1 within which is located a flanged plug n^2 having a conical seating which is mounted upon a conical stud n^3 attached to a hollow boss c on the drum C . The spindle n is rigidly connected to the soft iron armature e of the solenoid E , and positioned between the end of the armature e and the flanged plug n^2 is a light spring n^4 . The parts of the mine are preferably held together at the moment of launching by delay action means constituted by a hydrostat, a dashpot, a soluble plug or other suitable device, the construction of which is such that the parts of the mine are held together for a predetermined interval after launching.

A suitable form of hydrostatic device for allowing the mine to separate from the sinker when the combination has descended to a safe depth of immersion for the flotation chamber, is shown at Figure 2, the device comprising a hydrostat P and two links R, R^1 which respectively connect the parts of the hydrostat to the flotation chamber A and to the sinker B . The diaphragm p of the hydrostat is open through passages p^1 to the hydrostatic pressure, and it is connected to a spindle p^2 surrounded by a spring p^3 and the spindle is provided at its upper end with a plunger which is slidably mounted within a central recess r in the link R . Positioned within lateral slots in the link

R and projecting into recesses in the casing of the hydrostat are the balls s, s of a ball releasing device, the balls, in the position of the parts shown at Figure 2, rigidly holding together the hydrostat P and the link R . The operation of the mine is as follows:— When a safe depth of submersion for the mine has been reached, (position 2, Figure 1) the water pressure, acting on the diaphragm p , overcomes the spring p^2 and draws down the spindle p^3 and the plunger at its upper end until the balls s are free to move into the recess r and thus to release the casing of the hydrostat from the link R , whereupon the flotation chamber A separates from the anchor B , the sinker descending and the mine slowly ascending with the mooring cable paying out under the control of the oil pump brake K . As long as the flotation chamber is beneath the desired depth of submersion (position 3, Figure 1) the electric circuit will be closed by the hydrostatic switch and the excitation of the solenoid coils E will retract the soft iron armature e which is connected to the piston valve m by the light tubular spindle n thus pulling down the piston valve so as to open the return passage k^2 of the pump, and permitting the pump brake K to work at a speed corresponding to the rate of descent of the anchor with the mine remaining at about constant depth, that is at such a speed that the tension maintained in the mooring cable by the resistance of the brake is approximately equal to the buoyancy of the mine. The adjustment of the brake to suit this condition is previously fixed by adjustment of the screw valve l^3 . If the mine rises above the set depth of immersion the diaphragm g of the hydrostatic switch will move outwards and the switch will be broken and the solenoid de-energized. The spring n^4 will then move back the armature and close the valve m so as entirely to block the return passage of the pump K . The rotation of the mooring rope drum is then stopped and the mine will be drawn down by the anchor until the set depth is again reached or passed (position 4, Figure 1) whereupon the hydrostatic switch again operates to open the piston valve m thus permitting the pump brake to rotate and the mooring rope to pay out as before. A further length of mooring cable will accordingly be paid out. This action will continue until the anchor reaches the sea bed and, on account of the hydrostatic device, the flotation chamber will also come to rest at the depth below the surface for which the hydrostat was originally set (position 5, Figure 1). On reaching the sea bed a pawl or equivalent device is actuated and permanently locks the mooring cable drum. In its simplest form, the electro-magnetic releasing device may also be constituted by

a solenoid or catch which normally locks the mooring cable drum against rotation, but which, on the hydrostat being operated and the circuit through the mooring cable 5 being completed at the desired depth at which the flotation chamber is to be anchored, will release the mooring cable drum so as to allow the mooring cable to pay out. Instead of an electro-magnetic locking device, the drum of the mooring cable may be provided with a flange within which is located a two-part spring controlled expandable clutch actuated by an electric motor. The battery, hydrostatic apparatus and electric motor are in circuit with one another and, on the hydrostat being operated, the aforesaid electric motor operates to expand 10 the clutch into contact with the flange on the mooring cable drum, so as to stop the paying out of the mooring cable, which, due to the weight of the sinker and the buoyancy of mine, will, when the drum is unlocked, allow these parts to separate automatically from one another. An auxiliary hydraulic 15 brake can also, if desired, be provided so as to control the speed at which the mooring rope is paid out from the mooring cable winch drum. The anchor may also be provided with auxiliary anchoring means in addition to the device for permanently locking 20 the drum when it reaches the sea bed, while the battery (or batteries) instead of being located within the sinker may be located within the flotation chamber or within a casting attached to the flotation chamber. 25

It will be clear, therefore, that by means of the aforesaid arrangement the flotation chamber will remain, during the paying out of the mooring rope at approximately the 30 depth at which it is to be finally anchored, so that it is effectually prevented from being carried to a depth at which it is liable to be crushed by the hydrostatic pressure. Furthermore, and on account of the fact that 35 the parts of the flotation chamber and sinker, as also the battery, electro-magnetic locking device or motor and clutch device can be standardized for mines of any type, the cost of the mines is substantially reduced. The mine during the anchoring operation 40 will tend to pursue a zig-zag course, but a descent in a substantially straight line may be assured by making the parts sufficiently sensitive. The mine is equally suitable 45 for launching either from a submarine or from a surface vessel. When launched from a submarine the mine will not reach the surface so that no indication will be given to surface craft, either of the presence 50 of the mine or the submarine.

What I claim and desire to secure by Letters Patent of the United States is:—

1. A submarine mine comprising a flotation chamber, a sinker, a mooring cable connecting said flotation chamber to said sinker, 55

means permitting said mooring cable to unwind and said sinker to separate from said flotation chamber until it reaches the sea bed, and means for maintaining the flotation chamber at substantially a predetermined depth below the surface until the sinker reaches the sea bed. 70

2. A submarine mine comprising a flotation chamber, a sinker, a mooring cable connecting said flotation chamber to said sinker, 75 and means which allow the mooring cable to unwind and the sinker to sink towards the sea bed as long as the flotation chamber is below a predetermined depth, said means also acting to stop the paying out of the 80 mooring cable should the flotation chamber rise above the said depth.

3. A submarine mine comprising a flotation chamber, a sinker, a mooring cable connecting said flotation chamber to said sinker, 85 hydrostatically operated mechanism, and means within said sinker controlled by said hydrostatically operated mechanism for allowing said mooring cable to unwind and said sinker to separate from said flotation 90 chamber until the sinker reaches the sea bed, said hydrostatically operated mechanism also acting to stop the unwinding of the mooring cable should the flotation chamber rise above a set depth beneath the surface. 95

4. A submarine mine comprising a flotation chamber, a sinker, a mooring cable connecting said flotation chamber to said sinker, hydrostatically operated mechanism 100 which comes into operation at substantially the depth at which the flotation chamber is to be finally anchored, controlling means within said sinker actuated by said hydrostatically operated mechanism for allowing the mooring cable to unwind as long as the flotation chamber is below the set depth said hydrostatically operated mechanism also serving to throw out of operation 105 said controlling means and to stop the unwinding of the mooring cable should the flotation chamber rise above the said depth. 110

5. A submarine mine comprising a flotation chamber, a sinker, a mooring cable connecting said flotation chamber to said sinker, electrical conductors within said mooring cable, hydrostatically operated means positioned on said flotation chamber and adapted to bridge said conductors when the flotation chamber is below a set depth 115 and means within said sinker in circuit with said conductors for allowing said mooring cable to unwind and the sinker to separate from the flotation chamber as long as said conductors are bridged. 120

6. A submarine mine comprising a flotation chamber, a sinker, a mooring cable connecting said flotation chamber to said sinker, braking means permitting said mooring cable to unwind at a speed corresponding 130

to the rate of descent of the sinker as long as the flotation chamber is at substantially a predetermined depth, and means for maintaining the flotation chamber at substantially said predetermined depth until the sinker reaches the sea bed.

7. A submarine mine comprising a flotation chamber, a sinker, a drum within said sinker, a mooring cable upon said drum, said mooring cable connecting said flotation chamber to said sinker, electrical conductors within said mooring cable, terminals at one end of said electrical conductors, hydrostatically controlled means adapted to bridge said terminals, a releasing device for said mooring cable drum, and a source of supply of electric current, in circuit with said re-

leasing device and said conductors for the purpose specified.

8. A submarine mine comprising a flotation chamber, a sinker, a mooring cable connecting said flotation chamber to said sinker, means for releasing the flotation chamber from the sinker as soon as the mine reaches a depth below which depth the flotation chamber is liable to be damaged by the hydrostatic pressure, and means which allow the mooring cable to unwind and the sinker to sink to the sea bed as long as the flotation chamber is below a set depth but which stop the unwinding of the mooring cable should the flotation chamber rise above said set depth.

GIOVANNI EMANUELE ELIA.
